Office Action from Canadian Patent Application No. 160,158, mailed May 29, 2015 (2 pages).

Primary Examiner — Kelley Donnelly(74) *Attorney, Agent, or Firm* — JoAnn M. Seaton;
Griffiths & Seaton PLLC(57) **CLAIM**

The ornamental design for a merchandise display bar, as shown and described.

DESCRIPTION

FIG. 1 is a front, perspective view of a merchandise display bar showing our new design;

FIG. 2 is a front view thereof, the rear view being a mirror image of the front view;

FIG. 3 is a right side view thereof, the left side view being a mirror image of the right side view; and

FIG. 4 is a top view thereof, the bottom view being a mirror image of the top view.

FIG. 5 is a front, perspective view of the merchandise display bar of FIG. 1 shown with the additional environmental subject matter of a display rack and a supported display rod;

FIG. 6 is a front view thereof;

FIG. 7 is a rear view thereof;

FIG. 8 is a right side view thereof, the left side view being a mirror image of the right side view; and,

FIG. 9 is a top view thereof.

The features shown in broken lines are environmental subject matter to the merchandise display bar forming no part of the claimed design.

1 Claim, 6 Drawing Sheets---
